Wallace Lafayette, ^{Inventor} Sellick.

by *David Moore.*
Attorney.

UNITED STATES PATENT OFFICE.

WALLACE LAFAYETTE SELLECK, OF DARLINGTON, WISCONSIN.

HYDRANT.

SPECIFICATION forming part of Letters Patent No. 783,900, dated February 28, 1905.

Application filed December 28, 1903. Serial No. 186,871.

To all whom it may concern:

Be it known that I, WALLACE LAFAYETTE SELLECK, a citizen of the United States, residing at Darlington, in the county of Lafayette and State of Wisconsin, have invented 5 certain new and useful Improvements in Hydrants, of which the following is a specification.

My present invention relates to improvements in hydrants, and has special reference 10 to a hydrant in which no packing is employed and which is so arranged as not to be affected by the frost.

To attain these objects, the invention consists of novel features of construction and 15 combination of parts, substantially as set forth herein.

In the accompanying drawings, Figure 1 is 20 a side elevation of a complete hydrant. Fig. 2 is a vertical sectional view thereof, showing the parts in the position they assume when water is flowing from the hydrant. Fig. 3 is 25 a similar view showing the parts in the position they assume when water is shut off. Fig. 4 is a sectional view taken on line *xx* of Fig. 3.

Referring to the drawings, the numeral 1 30 designates the entrance-pipe, which is secured to the barrel 2, provided upon one wall with the downwardly-extending portion 3 and the upper threaded end 4. Mounted within the 35 barrel is a disk 5, which has secured thereto a downwardly-extending wall 6, which provides a curved channel 7, leading from the lower end of the barrel to a point above the disk 5, as clearly shown in Figs. 2 and 3. Having 40 its ends secured to the threaded end 4 of the barrel is a head 8 of the hydrant, which is provided with a cap 9 and an outlet-spout 10, and surrounding the cap and extending below is 45 a casing 11, which is employed to prevent the frost from affecting the hydrant. Passing through the cap of the hydrant and extending down through the disk 5 is an operating-rod 12, whose lower end is secured to the dome 13 of the valve 14. This valve is adapted to 50 be raised or lowered within the chamber 15 of the barrel 2, so as to control the passage of water through the channel to the upper end of the barrel and out through the spout of the hydrant. When the valve is raised, it as-

sumes the position as shown in Fig. 3 and water is prevented from passing through the channel 7, and the dome 13 enters the recess 16 in the bottom of the disk 5 and closes all leakage through the opening 17, through 55 which the rod 12 is adapted to slide.

The valve 14 is of a peculiar construction and is composed, respectively, of the downwardly-projecting stationary guide-wall 18 and the hinged flap or wall 19, which is provided with an opening 20. This wall or flap 19 is hinged at 21, by means of the two lugs 22^a and 23, respectively, (clearly shown in Fig. 4,) to the upper portion 13 of the valve, and by reason of the pressure of water from 60 below the flap 19 is adapted to spread outward, so as to tightly impinge the sides of the wall of the barrel 2, and when the entire valve 14 is moved up or down by the rod 12 the flap 19 will control the flow of water from 65 the lower part of the barrel to the upper end thereof. When the valve is held upward in 70 its upmost position, as shown in Fig. 3, the solid portion of the flap 19 will be opposed to the lower end of the channel 7 and will prevent any passage of water therethrough, and when lowered, as in Fig. 2, the opening 20 will be in line with the mouth of the channel 7 and will allow free passage of the water from 75 the lower end of the barrel through the hydrant. The pressure of water from below will always tend to move the flap 19 outward, so as to keep its outer surface in close contact with the interior of the barrel in the chamber 80 15 and the wall 6. Thus when the valve is in 85 the position as shown in Fig. 3 no water is allowed to flow to the channel 7; but as soon as the valve is lowered, as in Fig. 2, the water is allowed to pass through the opening 20, 90 through the channel 7, and out of the hydrant. 90

From the foregoing description, taken in connection with the drawings, it is evident that I provide a hydrant embodying novel features of construction and one which will be protected from the frost or freezing and is 95 therefore thoroughly efficient and practical in use.

What I claim as new, and desire to secure by Letters Patent, is—

1. In a hydrant, the combination of a bar-

100

rel provided with an inlet-opening, a disk having a downwardly-extending wall mounted within the barrel providing a valve-chamber and dividing the barrel into an upper and lower 5 communicating chamber, a valve slidably mounted within the valve-chamber provided with a hinged wall having an outlet, a removable cap carrying a spout secured to the upper end of the barrel and means passing through 10 the cap and connected to the valve for operating the valve.

2. In a hydrant, the combination of a barrel provided with an inlet-channel, a disk having a downwardly-extending wall mounted 15 within the barrel providing a valve-chamber and dividing the barrel into an upper and lower communicating chamber, a valve slidably mounted within the valve-chamber provided with a hinged wall having an outlet, a removable cap carrying a spout secured to the upper 20 end of the barrel, means passing through the cap and connected to the valve for operating

the valve, and a jacket surrounding the barrel and cap projecting above and below the junction thereof, for the purpose set forth. 25

3. In a hydrant the combination of a barrel provided with an outlet-opening, a disk having a downwardly-extending wall mounted within the barrel providing a valve-chamber and dividing the barrel into an upper and lower 30 communicating chamber; a valve mounted within the valve-chamber provided with an outlet, a removable cap carrying a spout secured to the upper end of the barrel, and means passing through the cap and connected to the 35 valve for operating the valve, for the purpose set forth.

In testimony whereof I affix my signature in presence of two witnesses.

WALLACE LAFAYETTE SELLECK.
